Clayton Jenkins

ATTORNEY

UNITED STATES PATENT OFFICE

ALEXANDER I. SNOW, OF WORCESTER, MASSACHUSETTS, ASSIGNOR TO RILEY STOKER CORPORATION, OF WORCESTER, MASSACHUSETTS, A CORPORATION OF MASSACHUSETTS

AUTOMATIC STOKER

Application filed May 9, 1927. Serial No. 189,905.

This invention relates to automatic stokers, and more particularly to means for controlling the air flow to the fuel supporting surfaces thereof.

In an automatic stoker which is arranged to introduce fuel into the front part of a furnace and transport it progressively towards an ash dump at the rear of the furnace, the air requirements of any particular portion of the fuel bed vary according to its distance from the point of entrance. This has been recognized, but various difficulties have been encountered in attempting to provide a suitable air control, particularly with stokers of the multiple retort underfeed type. The use of partitions or other obstructions in the air chamber beneath the retorts is undesirable because they make it difficult to remove the siftings which accumulate. In stokers of the type shown in the U. S. patent to Riley No. 1,090,651 various parts of the fuel supporting structure are reciprocated and the problem of providing suitable air zoning in such a stoker is thereby complicated. Similar problems are encountered in other types of stokers in which reciprocating air delivery means are utilized.

It is accordingly one object of my invention to overcome such difficulties and to provide, in connection with a multiple-retort underfeed stoker, a simple and convenient mechanism for controlling the air flow from front to rear of the stoker without obstructing materially the air chamber beneath, and particularly to provide an arrangement for controlling the air flow to reciprocating air distributing members as used in automatic stokers of various types. Further objects are to provide a stoker having parallel retorts and tuyères with localized air zoning so arranged that the air flow to one group of tuyères may be regulated independently of the air control for another group, and particularly to provide such a construction which is capable of use in a stoker having reciprocable tuyères.

A further object is to provide localized air zoning in an underfeed stoker having several parallel retorts and to so arrange the parts that the air pressures at corresponding

groups of tuyères across the stoker may be controlled simultaneously to form air zones.

Another object is to provide a control device for regulating the air admitted to the tuyères of a stoker which is so constructed that heat expansion of parts of the stoker will not affect the regulation of the air flow.

With these and other objects in view as will be apparent to those skilled in the art, my invention resides in the combination of parts set forth in the specification and covered by the claims appended hereto.

In accordance with my invention, I provide for localized air zoning in a stoker, whereby air is admitted to local groups of one or a few tuyère blocks, two being illustrated, so that air may be admitted to each group through separately controlled channels, whether used for feeding air to the same retort or to the corresponding tuyère blocks across the stoker, and I so arrange the parts that the air may be separately controlled in parallel zones extending at right angles to the retorts. This invention particularly contemplates localized air zoning to the tuyères blocks mounted in reciprocable side bars in a stoker of the Riley type.

In one embodiment of my invention, I provide a stoker having a plurality of underfeed retorts arranged parallel to each other and extending from front to rear of a furnace. To provide for localized air zoning, the longitudinally extending side bars or members which form the sides of the retorts may be formed hollow and left open at the bottom to permit the entrance of air from a suitable air chamber beneath the stoker. The tuyère blocks which are arranged to form a support for the fuel bed and distribute air thereto may be of any suitable construction and are mounted on top of the hollow side bars. The space within each side bar is divided into a number of separate air passages by means of a plurality of partitions extending transversely of the side bar and preferably in substantially vertical planes. By means of this construction, it is apparent that each air passage will deliver air to a comparatively small localized group of tuyère blocks. I arrange a suitable damper device for control-

ling the air flow to each passage in the side bar and correspondingly located damper devices in the different side bars may be connected together across the stoker and arranged to be controlled from a point convenient to the stoker operator to provide a number of parallel air zones.

Referring to the drawings illustrating one embodiment of my invention and in which like reference numerals indicate like parts:

Fig. 1 is a side view of a stoker applied to a furnace, the parts within the furnace being shown in section on the line 1—1 of Fig. 3;

Fig. 2 is a partial section on the line 2—2 of Fig. 1, parts being broken away;

Fig. 3 is a similar view on the line 3—3 of Fig. 1;

Fig. 4 is a section on the line 4—4 of Fig. 3, a part only of the stoker being shown; and

Fig. 5 is a perspective view of a damper device and its controlling member.

In the drawings I have illustrated my invention as applied to a stoker of the multiple-retort underfeed type. This comprises a fuel hopper 10 of suitable construction which is mounted adjacent to a vertical front wall 11 of a furnace. Mounted beneath the hopper and arranged to receive fuel therefrom are a plurality of horizontal cylindrical ram casings 12. A suitable ram, not illustrated, is arranged to be reciprocated within each ram case by a rotatable crankshaft 14, as is well known in this art. This crankshaft is arranged to be rotated at a slow speed through a suitable gear reduction device 16 which is connected to a desired source of power. The weight of the ram casing and associated parts may be supported on pipe columns 17 which rest on a concrete floor 18.

A plurality of parallel underfeed retorts 20 extend rearwardly from the front wall 11. These retorts are provided with stationary bottom plates 21 which incline downwardly at a slight angle towards the rear of the furnace. The sides of the retorts are formed by the side bars 24 which are arranged to support on their upper surfaces the tuyère blocks 25. These tuyère blocks may be arranged in steplike formation as illustrated in rows extending longitudinally of the stoker between the retorts, and may be of any suitable construction to form a support for the fuel bed and deliver air thereto.

In the embodiment illustrated, I have shown these side bars as being suitably constructed for horizontal reciprocation. For this purpose each side bar is supported at its forward end on a cylindrical member 26 which is mounted in a suitable slide bearing 28 forming an integral part of the ram casing. Each side bar is arranged to be reciprocated by its corresponding ram through a lost motion connection 30 in a manner well known in this art and fully disclosed in the patent

to Riley No. 1,090,651. At its lower and rearward end, each side bar is attached to a shoe 32 arranged to slide over the upper plane surface of a base plate 33 which is bolted to a pair of I-beams 35. These I-beams extend transversely of the stoker and rest in suitable pockets in the side wall of the furnace as will be well understood.

I prefer to provide an overfeed grate section 36, which may be of any suitable construction and which is mounted on the side bars 24 beneath the lower end of the retort 20. This overfeed grate serves as a tuyère structure to furnish air for the combustion of any unconsumed coke which issues from the lower end of the underfeed retort.

In the rear of the overfeed grate 36 I have illustrated one form of rocker grate member 38 which is preferably pivotally connected to the shoe 32 as described in the patent to Riley et al. No. 1,605,665. If desired, the upper portion of this rocker plate 38 may be a hollow construction as illustrated and provided with air openings to assist in burning out any combustible remaining in the ash and refuse supported thereon. The rocker plates rest at their lower ends on rolls 40 suitably mounted at the rear ends of horizontal rack bars 41. A vertical bridgewall 43 is arranged in the rear of the rocker plates and in substantial proximity thereto. The position of the rocker plates 38 in relation to the bridgewall may be adjusted by means of a horizontal shaft 45 mounted in suitable brackets 46 which are bolted to the forward I-beam 35. This shaft carries a series of pinions 48 which mesh with the teeth on the rack bars. It will be understood that the shaft 45 extends through the side walls of the furnace and is arranged to be controlled from a convenient point.

A suitable vertical plate 50 is mounted beneath the front wall 11 of the furnace so as to entirely enclose the space beneath the stoker retorts and form a pressure chamber 52. Air may be supplied to this pressure chamber from any suitable forced draft apparatus, such as a fan, through a duct 53 which may be provided with a suitable damper 54. Air is delivered to the tuyère blocks 25 and overfeed grates 36 from the air chamber 52 through the side bars 24, which, as shown clearly in Figs. 2 and 3, are of hollow construction. The air for the rocker dump plates 38 passes through the base plates 33 and shoes 32, as shown clearly in Fig. 1, and this air may be controlled if desired by dampers 54 mounted on a horizontal rotatable shaft 55 which, it will be understood, extends through the side wall and can be controlled from the outside of the furnace.

In the operation of a stoker of this type, combustion proceeds progressively from ignition at the front of the stoker to the ash

which is discharged at the rear. For this reason the character of the fuel bed is constantly changing and the requirements as to air pressure and volume are different at each 5 stage of combustion. These changes are very marked and a decided difference in air pressures and volume at each point along the grate surface is frequently necessary. Moreover the requirements of air pressure and 10 distribution vary widely for different fuels and with different rates of combustion.

In order to provide a construction by means of which the air flow to different parts of the fuel bed may be conveniently controlled by the stoker operator without the necessity of complicated dividing walls which obstruct the air chamber beneath the stoker and make it extremely difficult to remove siftings therefrom, I arrange within 15 the interior of each hollow side bar 24 a series of transverse partition walls 58 which are shown clearly in Fig. 4. These walls 58 are preferably arranged in vertical planes as illustrated, as this construction permits 20 any fine coal which may sift through the openings in the tuyère blocks to fall freely into the air chamber 52, rather than obstruct the air passages as would otherwise occur. It will be seen from an inspection of Fig. 4, 25 that this construction provides a series of localized air passages through the side bars which connect with a comparatively small portion of the fuel supporting surface. I have shown one passage as leading to the 30 overfeed grate section 36 and a separate passage leading to each pair of tuyère blocks 25. With this construction, each row of tuyère blocks is divided by the partitions into localized groups consisting of pairs of tuyère 35 blocks. It is, however, apparent that there may be more or less of these partition walls 58 depending upon the degree of air control which is desired, and each passage may supply air to one or more tuyère blocks in such 40 localized groups.

Each air passage through the side bars 24 is provided with a suitable damper, which in the embodiment illustrated comprises a substantially flat rectangular plate 60 provided on its upper surface with a pair of up-standing lugs 61 having holes 62 therethrough. The lugs 61 are arranged off center on the plate 60 for a purpose which will be described later. Each damper plate 60 is 50 pivotally mounted in the side bars on a horizontal rod 64 which extends in the direction of the side bar reciprocation. These rods 64 are mounted in the partition plates 58 55 in the side bars and pass through the openings 62 in the lugs 61. Each damper plate 60 is provided with a pair of downwardly depending arms 66 attached to its lower surface for the purpose of controlling its pivotal adjustment. These arms are connected 60

by a rod or bar 67 which is arranged parallel to the rod 64.

In order to permit simultaneous adjustment of the correspondingly located dampers in the different side bars, and thus form 70 parallel air zones extending laterally of the retorts, I provide a suitable connecting member arranged transversely of the stoker. In the embodiment illustrated, this member comprises an angle 70 in one leg of which a 75 series of notches 71 are provided. As shown each notch 71 is arranged to fit over one of the damper rods 67. As heretofore described, the lugs 61 on the damper plates are arranged off center and this causes each damper to be 80 unbalanced so that it tends to close by its own weight. There is a particular advantage in this form of construction due to the fact that considerable expansion takes place in a stoker because of the heat of the furnace 85 and this is particularly apparent in a wide stoker. By making the rods 67 fit rather loosely in the notches 71 it is apparent that the dampers 60 will all close by their own weight regardless of any expansion which 90 may take place in the stoker structure. The angle 70 is affected very little by the heat of the furnace as it is subjected to the air flow through the chamber 52 and for this reason if the dampers 60 were balanced and the 95 notches 71 were made a tight fit, it would result from expansion of the stoker that certain dampers might be closed while others connected thereto would be partially open.

In Fig. 2 I have illustrated one simple 100 means for controlling the position of the angles 70 and hence the opening of the dampers connected thereto. Each angle 70 has mounted thereon a small depending lug 75 to which is pinned a connecting link 76 which 105 extends horizontally through a small opening 78 in the side wall 80 of the furnace. A substantially vertical lever 82 is pivotally mounted in a bracket 83 on the outside of the furnace side wall and is pinned to the outer end 110 of the link 76. An arc-shaped member 85 may be mounted on the outside of the furnace wall in a suitable position and the lever 82 may be clamped thereto at any desired point of adjustment by means of a thumb 115 screw 86. It will be understood that there is a lever 82 provided for each zone of the stoker, there being seven of these zones in the stoker illustrated, exclusive of the rocker dump plates 38. In the case of an exceptionally 120 wide stoker, such as for example a stoker having sixteen retorts, it may be desirable to provide levers on each side of the furnace so that any particular lever will control the dampers from its corresponding side wall to 125 the center of the furnace.

The operation of my invention will now be apparent from the above disclosure. Coal is delivered to the underfeed retorts 20 from the hopper 10 by the reciprocating rams and 130

the fuel bed is carried rearwardly towards the bridgewall 43 by means of the reciprocating motion of the side bars and the tuyère blocks supported thereby. The fuel bed passes out of the lower end of the retorts and moves over the reciprocating overfeed grates 36 and dump plates 38 to the ash pit. It will be understood that the different side bars in the stoker are moving in different but parallel directions at the same time and as a result the rods 67 on the dampers 60 slide relative to the control members 70 which remain stationary except when it is necessary to make an adjustment by means of the corresponding lever 82. The air flow to any particular section of the fuel bed in relation to other sections may be conveniently controlled from an accessible point outside the stoker. This makes the operation of the stoker extremely flexible and adaptable to different rates of combustion and different types of fuel. By removing the front plate 50 or a small section thereof, it is a simple matter to obtain access to the air chamber 52 whenever it becomes necessary to remove therefrom an accumulation of fine coal or siftings. This air chamber is entirely unobstructed and no difficulty is encountered in effecting such removal. It is to be understood that the damper 54 will be utilized for varying the pressure in the air chamber 52 to take care of changes in the rate of burning fuel and that the dampers 60 will be utilized merely for varying the distribution of air to the fuel bed.

Having thus described my invention, what I claim as new and desire to secure by Letters Patent is:—

1. A stoker comprising a movable support for the fuel arranged to admit air thereto, said support including walls forming an air passage, an adjustable damper movable with said walls to control the air flow, and a stationary member adjustably mounted to vary the adjustment of the damper as desired.

2. A stoker comprising a reciprocable structure arranged to form a support for the fuel bed and deliver air thereto for combustion, said structure including walls so constructed as to form an air passage, a damper mounted in said air passage and arranged for pivotal adjustment about an axis extending in the direction of reciprocation, and a stationary member adjustably mounted for controlling the adjustment of the damper.

3. A stoker comprising a reciprocable structure arranged to form a fuel supporting and air admitting surface, said structure including walls so constructed as to form an air passage, a damper mounted in said passage and arranged for pivotal adjustment about an axis extending in the direction of reciprocation, a rod mounted on said damper parallel to said axis and spaced therefrom, and a stationary adjustable member arranged to

cooperate with said rod in varying the adjustment of the damper, said rod being arranged to reciprocate with the damper relative to the adjusting member.

4. A stoker comprising a plurality of structures arranged to form a fuel supporting and air admitting surface, means for reciprocating said structures relative to each other in parallel directions, each of said structures including walls reciprocable therewith and arranged to form an air passage, a damper mounted in each passage to control the flow of air therethrough, and a stationary adjustable member extending transversely of the direction of reciprocation and arranged to simultaneously adjust the position of a plurality of said dampers irrespective of the relative positions of said structures.

5. A stoker comprising a plurality of structures arranged to form a fuel supporting and air admitting surface, each structure including walls arranged to form an air passage, a damper pivotally mounted in each passage to control the flow of air therethrough and so arranged that it will tend to close, and an adjusting member arranged to simultaneously adjust a plurality of the dampers, said member being loosely connected to the dampers.

6. A stoker comprising a plurality of structures arranged to form a fuel supporting and air admitting surface, each structure including walls arranged to form an air passage, a damper pivotally mounted in each passage about an axis spaced from its center of gravity so that the damper will tend to close by its own weight, and a member arranged to simultaneously adjust a plurality of said dampers, said member being loosely connected to the dampers.

7. An underfeed stoker comprising separately reciprocable hollow side bars and bottoms forming parallel retorts, a row of tuyères for each side bar, partitions within the side bars forming separate air passages and dampers mounted on the side bars to control the flow of air in said passages.

8. An underfeed stoker comprising spaced walls defining parallel retorts, a row of tuyère blocks spanning the space between each pair of adjacent retort walls and extending lengthwise of the retorts, means forming separate air passages to localized groups of the tuyères in each row, and a separate regulatable control device for each of said groups so that the air pressure to one of said groups may be regulated independently of that to another of the groups in the same row.

9. An underfeed stoker comprising spaced walls forming parallel retorts, a row of tuyère blocks spanning the space between each pair of adjacent retort walls and extending lengthwise of the retorts, walls forming separate air passages to localize groups of tuyères in each row, a damper to regulate the air

flow in each passage independently of other passages in the same row, and connections to operate together those dampers which control the air flow to tuyère groups arranged laterally of each other, thereby forming air zones which extend at right angles to the retorts.

10. An underfeed stoker comprising spaced walls defining retorts, a row of tuyère blocks spanning the space between the walls of adjacent retorts and extending lengthwise thereof, means forming a chamber for air under pressure beneath said retorts, means forming separate air passages between adjacent retort walls leading from said air chamber to localized groups of tuyère blocks, means adjacent to one of said passages to control the air pressure therein independently of the air pressure in another of said passages in the same row, and means for operating said control means from a point outside of said air chamber.

11. An underfeed stoker comprising walls forming spaced parallel retorts, rows of tuyère blocks mounted on said walls between the retorts and extending lengthwise thereof, means forming a chamber for air under pressure beneath said retorts, means forming independent air passages between adjacent retort walls leading from said chamber to localized groups of tuyère blocks in each row, a damper mounted adjacent to each of said passages to control the air flow therethrough, and means for controlling the position of one of said dampers from a point outside of said air chamber independently of another of said dampers which is connected with tuyère blocks in the same row.

12. An underfeed stoker comprising a plurality of hollow side bars arranged parallel to each other and spaced apart to form retorts therebetween, tuyère blocks mounted on the side bars, means forming an air chamber for the introduction of air under pressure beneath the side bars, partitions in the side bars arranged to provide a plurality of independent air passages through each side bar, dampers mounted in certain of said air passages to control the flow of air to the tuyères connecting therewith, and means for simultaneously operating correspondingly located dampers in different side bars independently of other dampers, whereby the air flow may be controlled in zones extending transversely of the retorts.

13. An underfeed stoker comprising a plurality of hollow reciprocable side bars arranged parallel to each other and spaced apart to form retorts therebetween, tuyère blocks mounted on the side bars, means forming an air chamber for the introduction of air under pressure beneath the side bars, partitions in each side bar arranged to provide a plurality of independent air passages therethrough, a damper mounted in each air passage and reciprocable with the side bar, and

means for simultaneously adjusting correspondingly located dampers in different side bars.

14. An underfeed stoker comprising a plurality of hollow reciprocable side bars arranged parallel to each other and spaced apart to form retorts therebetween, tuyère blocks mounted on the side bars, means forming an air chamber for the introduction of air under pressure beneath the side bars, partitions in the side bars arranged to form a plurality of independent air passages through each side bar, a damper pivotally mounted in each air passage about an axis extending in the direction of reciprocation, said dampers being reciprocable with the side bars, and an adjusting member extending transversely of the retorts and arranged to simultaneously adjust correspondingly located dampers in different side bars.

15. An underfeed stoker comprising a plurality of hollow reciprocable side bars arranged parallel to each other and spaced apart to form retorts therebetween, tuyère blocks mounted on the side bars, means forming an air chamber for the introduction of air under pressure beneath the side bars, substantially vertical partitions in the side bars arranged to form a plurality of independent air passages through each side bar, a damper pivotally mounted in each air passage about an axis extending in the direction of reciprocation, said damper being reciprocable with its bar, a rod mounted on each damper parallel to said axis and spaced therefrom, stationary adjustable members extending transversely of the retorts and connecting the correspondingly located rods at the different side bars, and means for adjusting each member independently of the others from a point outside the air chamber.

16. A stoker comprising a plurality of parallel bars having tuyère blocks thereon and reciprocable longitudinally in different but parallel directions at the same time, means including dampers movable with said bars arranged to control the air flow to the tuyère blocks, and means to simultaneously operate a group of dampers in a row extending transversely of the bars irrespective of the relative positions of the bars.

Signed at Worcester, Mass., this fifth day of May, 1927.
